TABLECLOTH

Howard D. Hooven, deceased, late of Doylestown, Pa., by Florence S. Hooven, executrix, Doylestown, Pa., assignor to Quaker Lace Company, a corporation of Pennsylvania

Application August 17, 1951, Serial No. 16,336

Term of patent 14 years

(Cl. D92—26)

To all whom it may concern:

Be it known that I, Florence S. Hooven, executrix of the last will and testament of Howard D. Hooven, late a citizen of the United States of America and resident of Doylestown, State of Pennsylvania, deceased, a citizen of the United States of America, residing at Doylestown, in the county of Bucks and State of Pennsylvania, have a new, original, and ornamental Design for a Tablecloth, invented by the deceased, of which the following is a specification, reference being had to the accompanying drawing, forming a part thereof, in which the figure is a face view of a quarter section of the tablecloth, showing his new design, the other three sections being identical with that here disclosed, arranged in proper relation to complete the tablecloth. The quarter section is shown over a dark background to bring out the details of the design.

It is claimed:

The ornamental design for a tablecloth, substantially as shown and described.

FLORENCE S. HOOVEN,
Executrix of the Last Will and Testament of Howard D. Hooven, Deceased.
